UNITED STATES PATENT OFFICE.

JOHN DOHERTY, OF COXSACKIE, NEW YORK, ASSIGNOR TO SUPERIOR PROJECTOR, INC.,
OF COXSACKIE, NEW YORK, A CORPORATION OF NEW YORK.

MOTION-PICTURE TAKE-UP APPARATUS.

Application filed January 16, 1923. Serial No. 612,920.

To all whom it may concern:

Be it known that I, JOHN DOHERTY, a citizen of the United States, residing at Coxsackie, in the county of Greene and State of New York, have invented certain new and useful Improvements in Motion-Picture Take-Up Apparatus, of which the following is a specification.

My present invention relates to take-up or winding devices particularly adapted for use with motion picture projecting apparatus, which invention will best be understood from the following description and the appended drawings in which I have shown an illustrative embodiment of my invention.

In the drawings, Fig. 1 is a front elevation of a take-up mechanism of a motion picture projecting machine, with some of the parts broken away on the line 1—1 of Fig. 2 for the sake of clearness; Fig. 2 is a side elevation of the illustrative form of apparatus; Fig. 3 is a section on the line 3—3 of Fig. 2, and Fig. 4 is a more or less diagrammatic representation of the film and guide rollers looking from the left of Fig. 1.

Like reference characters indicate like parts in the several views.

In the illustrative embodiment, 10 represents a portion of the usual base or support for a motion picture apparatus, and 11 a portion of the projecting head which carries the usual film-moving mechanism.

In the specific arrangement illustrated, the machine is driven from a power shaft 12 through spiral gears 13, 14. The gear 14 is connected to a vertical shaft 15 carried in suitable bearings and motion is transmitted to the driving gears 16, 17 in the machine head through a spiral gear 18 on the shaft 15. The film-feeding sprocket 19 is driven by a gear 20 from the gear 17, the sprocket 19 turning continuously while the machine is in motion to feed the film 11 downward from the projecting machine head in the usual manner.

Supported on the base 10 by a bracket 21 is a reel shaft 22 supported in suitable bearings and arranged to have connected thereto the usual reel 23.

The film F passing from the sprocket 19 is guided between pairs of guide rollers 24, 25 to the reel 23.

The arrangement described above is a usual one, and further description thereof

will be unnecessary to those skilled in the art.

As the film is taken up by the reel 23, the diameter of the roll increases in size, so that if the turning movement or torque of the reel is constant, the tension on the film becomes so great that it may break when the roll is small, if this torque is sufficient to take up the film when the roll is large.

By my invention I have provided means by which the torque can be maintained substantially constant, regardless of the size of the roll of film on the reel 23.

The shaft 22 and with it the reel 23 is driven by a friction member 26 connected to the shaft 22 and having its periphery contacted by a driving friction disc 27, connected to the shaft 15 by means of a pin 28 projecting through a slot 29 in the shaft 15, so that while the disc 27 is turning with the shaft 15, it may be moved longitudinally of the shaft. Above the disc 27 is a washer 30 bearing against the hub of the disc 27, a spring 31 around the shaft 15 pressing against the washer 30 and abutting at the other end against a collar 32, screw-threaded on a fixed abutment 33. By screwing the collar 32 on the abutment 33 which is attached to the shaft 15, the pressure of the spring 31 on the disc 27 may be adjusted.

Between the washer 30 and the disc 27 is located a cup member 34 connected by pins 35 with slots in the end of a lever 36 pivoted at 37 in the frame and connected at its opposite end by a connecting rod 38 with a lever 39 on a shaft 40 carried in the head of the machine and having at its opposite end a lever 41 carrying the roller 42 which engages in a loop in the film F passing from the sprocket 19 to the guide rollers 24.

The cup member 34 is free to slide vertically on the hub of the disc 27 and, of course, is non-rotatable, and preferably I provide a ball-bearing construction between the walls of the cup 34 and the hub of the disc 27, so that there will be so little friction between the two that there will be substantially no tendency for the cup 34 to rotate. This ball-bearing arrangement is illustrated best in Fig. 3, but it will be understood that it is not essential to my arrangement.

With the parts in the positions shown in the drawings, the spring 31 is exerting its full pressure on the disc 27 to give the

greatest frictional contact between the disc 27 and the friction member 26, so that the torque on the reel 23 will be the greatest possible. This would be the condition when 5 the roll of film on the reel 23 is the largest. When the roll is small, however, this torque would produce a tension on the film F between the rollers 24 and the sprocket 19 to draw the roller 42 to the left of Fig. 4 and 10 this, in turn, would force the connecting rod 38 downward and lift the cup 34 up until it contacted with the washer 30 and relieve some of the pressure of the spring 31 on the disc 27, thus decreasing the torque 15 on the shaft 22. This release would, in turn, relieve the tension on the film F and permit the roller 42 to move back toward its original position. In other words, by 20 my arrangement the pressure of the spring 31, and with it the torque on the shaft 22, are controlled by the tension of the film, so that this tension may be maintained substantially constant, regardless of the size of 25 the roll of film on the reel 23.

25 It will be understood that the arrange-

ment which I have illustrated is merely one embodiment of my invention and that the construction may be varied within wide limits.

I claim:

In a take-up device for motion picture apparatus, a reel, a film-feeding roller, a movable roller engaged by the film as it passes from the film-feeding roller to the reel and arranged to be moved by the tension on the film, a friction disc connected to said reel, a driving shaft at right-angles to the axis of the reel, a driving disc connected to said shaft and movable longitudinally thereof, a fixed abutment on said shaft, a movable abutment on said shaft and adapted to bear against said driving disc, a spring between said abutments and connections between said movable abutment and said movable roller arranged to move said movable abutment against the pressure of the spring when the movable roller is moved by the tension of the film.

JOHN DOHERTY.
